[57] CLAIM

I claim the ornamental design for a climbing fixture for a playground structure, as shown and described.

DESCRIPTION

Fig. 1 is a perspective view of the climbing fixture for a playground structure.

Fig. 2 is a plan view of the climbing fixture for a playground structure; and,

Fig. 3 is a bottom end view of the climbing fixture for a playground structure.

The surface(s) or portion(s) of the article not shown in the drawing or described in the specification form(s) no part of the claimed design.
